UNITED STATES PATENT OFFICE

107,329

DESIGN FOR A PIANO

William Zaiser, Rockville Centre, N. Y., assignor
to The Rudolph Wurlitzer Company, De Kalb,
Ill., a corporation of Ohio

Application September 20, 1937, Serial No. 71,686

Term of patent 3½ years

To all whom it may concern:

Be it known that I, William Zaiser, a citizen of the United States, residing in Rockville Centre, county of Nassau, and State of New York, have invented a new, original, and ornamental Design for a Piano, of which the following is a specification, reference being had to the accompanying drawing, forming a part thereof.

In the drawing:

Figure 1 is a three-quarter perspective view showing the keyboard and one side of the piano embodying my new design, with both lids in raised position.

Figure 2 is a three-quarter perspective view on a reduced scale, showing the other side of the piano and the rear end.

Figure 3 is a front elevational view on a reduced scale.

Figure 4 is a detail plan section showing the pedals, and taken as indicated at line 4—4 on Figure 1.

The characteristic features of this design are the legs, the desk, the rectangular lyre,—the rings serving as props for the hinged lids, and the pedal pads of circular shape.

I claim:

The ornamental design for a piano substantially as shown and described.

WILLIAM ZAISER.
